ROCK DRILL

William J. McCallum, Islington, Ontario, Canada

Application February 18, 1935, Serial No. 6,942

4 Claims. (Cl. 255—64)

This invention relates to drills and particularly to the type employed in producing holes in rock formations for the purpose of inserting sticks of explosive.

5 In the mining of ores it is commonly the practice to drill holes of relatively small diameter, say about an inch and a quarter, and of considerable depth, say 10 or 15 feet at spaced points throughout a particular formation and to then 10 insert suitable charges of explosive in the holes so that a considerable quantity of the ore can be blasted out. A difficulty encountered in these operations is that the drills are dulled very quickly even when formed of special, hard, tool steels. 15 A drill can scarcely be used more than a minute before it requires resharpening. This means that in the course of a day a considerable number of drills are required and there must be kept on hand a large quantity of the drills or they must 20 be transported to and from the sharpening equipment at frequent intervals. In the use of the ordinary drilling equipment this matter of transportation is an important item in that the drill members carrying the cutting edges are long and 25 heavy and usually must be conveyed a considerable distance to the sharpening equipment. This equipment is ordinarily above ground while the drilling operations may be carried on as much as 5,000 feet or more below the surface.

30 Attempts have been made heretofore to reduce the transportation problem to a minimum by providing a detachable bit or cutting element at the end of the drill rod but these attempts have not proved successful for one reason or another. 35 They have ordinarily involved such an expensive construction as to make their use impracticable. Furthermore, they have usually involved the use of screw-threads at one point or another for the attachment of the cutting elements to the drill 40 rod. This has led to difficulties in view of the tendency of the parts to unscrew and become detached in the course of handling and use. Various other difficulties have been encountered and accordingly these prior devices have not 45 proved sufficiently satisfactory to justify the expense.

The present invention provides the advantages of a small, detachable bit, without the objectionable features of prior known devices. The construction is inexpensive, simple to produce, simple to employ, and thoroughly reliable in operation, enabling the use of a bit, with cutting portions formed of hard material, such as a high grade, hard steel, and with a retainer portion of a softer, more ductile but tough mate-

rial, capable of withstanding the shocks and strains to which the tool is subjected. Very simple and effective means are provided for attaching the cutting portions to the retainer and detachably connecting the retainer with the drill 5 rod. No screw-threads are employed for either of these purposes, and the construction is such that a complete bit may be produced for only a few cents. Thereby the bits may be used until they become dull and then discarded. It is possible, however, to resharpen and reuse the bits if desired, and the material in them may, in any event, be readily salvaged and reused.

10 Other features and advantages of the invention will appear from the detailed description of an 15 illustrative embodiment of the same which will now be given in conjunction with the accompanying drawing, in which

Figure 1 is an end view looking down upon the 20 cutting edges of a bit constructed in accordance with the invention but at a stage prior to the completion of the device.

Figure 2 is a view of the same incompletely 25 finished unit partly in side elevation, partly broken away and partly in section along the line 2—2 of Figure 1.

Figure 3 is an end view, similar to Figure 1, but of the completed unit.

Figure 4 is a view similar to Figure 2 but of 30 the completed unit, taken partly in section along the line 4—4 of Figure 3, and showing the bit in relation to a drill rod.

Figure 5 is a bottom view of the completed unit.

Figure 6 is a perspective view of one of the 35 hardened cutting nibs employed in the bit, and

Figure 7 is a detail view in vertical section through the upper portion of the retainer.

Referring now to the drawing, the main body of the improved bit comprises a retaining sleeve 40 or member 10. This is originally produced in the form indicated in Figures 1 and 2. The outer contour of the lower portion of the sleeve may appropriately be defined by a series of flat surfaces 11 separated by a series of rounded corners 45 12. A large, central opening or passageway 13 is formed through the entire retaining sleeve and the lower portion of this opening may conveniently be formed with four flat sides 14 presenting a substantially square cross section with four 50 rounded corners. The upper portion of the retaining sleeve is initially provided with a substantially circular contour 15 while the interior of this portion is provided with a series of inwardly extending triangular projections 16. 55

These projections are such as to provide a series of four recesses opening toward the center of the sleeve to form a cross. Each of these recesses is bounded on its three closed sides by walls 17, 18, and 19.

The retaining sleeve may be formed of any suitable, ductile, durable material capable of withstanding the shocks and strains incident to the drilling of rock. It need not be hard or wear-resistant, however, since none of the cutting is effected by this portion of the bit. It may appropriately be formed of a low carbon, ductile steel containing about .15 to .30% carbon. Such a steel may be readily worked in the manner required by the invention and affords a retainer that will cushion the shocks imparted to the drill in the course of drilling through rock. The sleeve may be formed in any convenient way, as by forging a suitable piece of the material or by casting the same in the desired shape or by suitably machining and otherwise forming a section of tubular stock into the desired configuration.

The cutting action of the bit is performed by a series of nibs 20 formed of any suitable, hard, cutting alloy, such as a steel having a high carbon content of between .5 and 1.5%. Each nib has its upper end provided with sloping surfaces arranged to present a ridge or cutting edge 21, which, in the use of the bit, is brought into engagement with the rock. In the construction illustrated four of the nibs 20 are inserted in the retainer 10 in such a way as to leave a square opening at the center whose sides are of somewhat smaller dimension than the width of the nibs. To permit this the inner corners of the nibs are beveled, as indicated at 22, throughout the portions that are brought into direct contact when the nibs are assembled in the manner shown. Each nib is formed with a downward extension or shank 23 which at its lower end is of substantially the same width as the distance between the surfaces 17 and 19 of the retainer. This enables the nibs to be freely inserted in the four recesses previously explained, that open into the center of the sleeve. The heads of the nibs are somewhat wider than the portions 23 and are adapted to overlie the upper surfaces of the triangular projections 16 as well as a portion of the surrounding wall of the retainer. As best shown in Fig. 2, the portions 23 of the nibs are not provided with parallel sides from top to bottom but are grooved or indented at the sides as indicated at 24. The purpose of this, as will be made clear later, is to provide for the anchorage of the nibs in the retainer. It is to be understood in this connection that while the depressions or indentations 24 are indicated as having a particular form, considerable latitude is permissible in the construction of the nibs. Any undercut or indented construction that will accomplish the desired anchoring may be employed. It will be understood that the length of the projection 23 in the direction of the edge 21 is such as to allow it to fit snugly in the recess bounded by the walls 17, 18, and 19.

Upon assembling the nibs in the retainer in the manner indicated the unit is placed in a machine capable of exerting an immense pressure upon the upper portion of the retainer at the four points intermediate the nibs. The pressure is sufficient to force the metal inwardly at these points causing it to flow into the recesses or indentations 24 in the nibs and producing indentations 25 in the outer surface of the retainer. If desired the retaining sleeve may be heated

prior to inserting the nibs and applying pressure. This would reduce the pressure required and increase the squeezing action upon the nibs due to the subsequent shrinking of the retainer.

It will be apparent that after the pressure has been applied the nibs will be very firmly held by the retainer. The walls 17, 18, and 19 will be squeezed into close contact with the three adjacent sides of each nib and the beveled surfaces 22 of the several nibs will be forcibly pressed together. Accordingly there is no danger of movement of the nibs relative to the retainer in any direction.

At one of the corners 12 of the retainer and near the bottom of the latter there is provided a transverse slot 26 extending to about the middle of the two adjacent flat surfaces 11. This slot forms a relatively narrow section or strip 27 adjacent the open end of the bit which may be readily pressed in to the extent indicated in Figure 4. A sharp blow by a reasonably heavy hammer will be sufficient to force the strip inwardly in this manner. The purpose of this is to enable quick and simple attachment of the bit to the end of a drill rod 28. This rod is preferably square in cross section so as to form a relatively snug fit within the opening 13 of the bit. A notch 29 is formed at one corner of the rod a short distance from the end to present a shoulder 30 for cooperation with the upper edge of the strip 27. The shoulder 30 is located at such a distance from the end of the rod that when it is properly engaged by the strip 27 the end of the rod is substantially in contact with the surface 31 provided at the inner ends of the nibs 20. It will be understood that the strip 27 is not forced inwardly into retaining position until after the retainer sleeve is applied over the end of the drill rod. One way of indenting the strip 27 is to support the bit and drill stem by means of an upward projection on an anvil that engages only the strip 27 and to then strike a sharp blow at the opposite corner of the bit, but other methods may be employed. The bit may be removed by any suitable and convenient method, as for example, by inserting the bit in a slotted anvil having a V-notch adapted to receive the drill stem but too small to permit the passage of the bit, and then imparting a quick movement to the drill stem in the direction of its axis. This will bring the inner end of the bit sharply against the wall of the anvil around the V-notch and will remove the bit from the stem. Or if desired a chisel or similar wedging implement may be driven into the space between the notch 29 and the strip 27 to pry the latter outwardly and thus enable removal of the bit or the strip 27 may be split open by means of a chisel. The bit may be discarded after removal, being scrapped and the steel being salvaged. A new bit will be applied to the drill rod as frequently as necessary to provide efficient drilling.

An opening 32 is preferably provided along the central axis of the drill rod in communication with the opening formed between the inner ends of the cutting nibs. This allows water or air or other cooling fluid to be supplied to the cutting edges, the fluid being permitted to pass outwardly again through the channels formed by the depressions 25 and the flat surfaces 11 and thence along the entire outer surface of the rod.

While the square formation of the rod 28 and opening 13 are preferred it will be understood that other arrangements permitting a torque to be transmitted from the rod to the retainer sleeve

may be employed. For example the rod and opening might have a hexagonal or any other polygonal form, or the rod and sleeve might have interfitting splines or a key and keyway or similar interfitting projections and recesses. Furthermore, the form and arrangement of the cutting nibs and the number employed in each retainer may be varied. Various other modifications will suggest themselves to persons skilled in the art and it will be understood, therefore, that the scope of the invention is not restricted to the particular form shown, but is defined in the following claims.

What I claim is:

- 15 1. In a device of the class described a drill rod having a polygonal outer contour, a detachable bit having a socket portion with an opening of corresponding polygonal cross section adapted to snugly fit the end of said rod and be applied thereto by a rectilinear sliding movement, said socket portion being formed of ductile material, cutting elements of hard, wear-resistant material firmly and permanently united with said socket portion, and inter-engaging shoulders carried directly by said rod and socket portion for retaining said parts in assembled relation, one of said shoulders being shiftable relative to the member by which it is carried into interengagement with the other shoulder, both 20 of said shoulders then being rigidly and unyieldingly held in interengaging relation.
- 25 2. In a device of the class described a drill rod, a bit adapted to be engaged with said rod by freely sliding it rectilinearly over the end of said rod, said rod and bit having cooperating sur-

faces non-circular in cross-section so arranged as to transmit a torque from one to the other, and interengaging means carried permanently and rigidly by said bit and rod and presenting interlocking shoulders positively preventing sliding movement between said bit and rod out of assembled relation, one of said means being shiftable with respect to the member by which it is carried. 5

3. In a device of the class described a drill 10 rod having a polygonal outer contour, a detachable bit having a socket portion with an opening of polygonal cross-section adapted to snugly fit the end of said rod and be applied thereto by a rectilinear sliding movement, and interengaging 15 means carried permanently by said rod and bit at one of the corners of the polygon for retaining said parts in assembled relation, one of said means comprising a part displaceable from normal into interengaging relation with the other 20 25 of said means and adapted to remain rigidly in such position.

4. In a device of the class described a drill rod having a polygonal outer contour, a detachable bit having a socket portion with an opening 25 of polygonal cross-section adapted to snugly fit the end of said rod and be applied thereto by a rectilinear sliding movement, a shoulder on said rod extending transversely thereof, and means carried by said bit formed and arranged to be 30 readily pressed inwardly and remain rigidly in such position to provide a projection to cooperate with the shoulder on the rod and prevent disengagement of the parts.

WILLIAM J. McCALLUM. 35
